ATTORNEY

UNITED STATES PATENT OFFICE.

ISAAC S. DEMENT, OF ST. NICHOLAS, FLORIDA.

COUNTING-WHEEL.

1,070,427.

Specification of Letters Patent.

Patented Aug. 19, 1913.

Application filed November 24, 1909, Serial No. 529,750. Renewed November 13, 1911. Serial No. 660,190.

To all whom it may concern:

Be it known that I, ISAAC S. DEMENT, a citizen of the United States, and a resident of St. Nicholas, in the county of Duval and State of Florida, have invented certain new and useful Improvements in Counting-Wheels, of which the following, when taken in connection with the drawing accompanying and forming a part hereof, is a full and 10 complete description, sufficient to enable those skilled in the art to which it pertains to understand, make, and use the same.

This invention relates to printing wheels used in registering, dating, numbering, adding and other like machines, where a re-setting of said wheels is desired.

One of the objects of the invention is to obtain a printing wheel by means of which a character printed therefrom will be of the 20 color of the material on which it is printed; and a wheel which can be used also for observation of the characters thereon, or, by reversing the bends on one of the members thereof a printing of the color of the ink 25 will be obtained; while at the same time said wheels and the shaft on which they are mounted are so connected that a plurality of said wheels on said shaft can be re-set at any one of said characters, (say zero), by a 30 single complete turn of said shaft. And a further object of the invention is to obtain a wheel and shaft of the kind named which is economically made, easy to operate, and durable.

35 In the drawing referred to I have illustrated a device embodying the invention provided with numerals from one to zero on its periphery, said numerals being raised out from said periphery; and I have also 40 illustrated a manner of making the device whereby the numerals, from one to zero, will be pressed into said periphery.

Figure 1 is a plan view of a blank provided with radial projections having figures 45 thereon. Fig. 2 is an edge elevation of the blank illustrated in Fig. 1. Fig. 3 is an elevation of the blank illustrated in Figs. 1 and 2, with the radial projections thereof turned to the right, when said blank is viewed as shown in Fig. 2, so that raised characters are obtained on the periphery of the wheel of which said blank is a member. Fig. 4 is an edge elevation of the blank 50 illustrated in Figs. 1, 2 and 3, with the radial projections thereon turned to the right, (in the same direction as in Fig. 3). Fig. 5 is an

edge elevation of the blank illustrated in Figs. 1 and 4, with the radial projections of said blank turned to the left, to obtain depressed characters on the periphery of the wheel of which said blank is a member. Fig. 6 is a front elevation of a blank disk, provided with a recess, forming an element in the device embodying the invention. Fig. 7 is a vertical sectional view of a wheel embodying the invention, including a section of the shaft constituting a member of the device. Fig. 8 is a vertical sectional view of the device viewed at an angle of ninety degrees to the view in Fig. 7. Fig. 9 is a perspective of a pawl of the kind used to actuate a plurality of the wheels of the device.

A reference letter applied to designate a given part is used to indicate such part throughout the several figures of the drawing, wherever the same appears.

A is a blank provided with the central aperture a , with the additional aperture a' , and with the peripheral lugs or ears B.

X are numerals forced out of (or into), 80 the body of the lugs or ears B. The numerals X, (which in the drawing commence with zero and end with nine), when viewed from one side of blank A appear raised and when viewed from the other side of said blank appear depressed.

C, C, are broken lines on which the several lugs or ears B are bent, (to the right or to the left as required), to lay at substantially right angles to the remainder of the 90 blank A, in the completed device. When the several ears B are bent to the right, as illustrated in Fig. 4, the numerals X appear as raised characters, and when said ears are bent to the left, as in Fig. 5, these numerals 95 appear as depressed characters. When the wheel member of the device is to be used as a printing wheel I bend these lugs or ears to the right as in Fig. 4, and when said wheels are to be observed through a slot or 100 other aperture I turn them to the left, as in Fig. 5.

D, Fig. 6, is a blank from which one member of the wheels of the device is obtained. d is a central aperture in blank D. d' is an 105 additional aperture in said blank, and D' is the portion of blank D which is forced into a cylindrical wall. E is a notch or recess on the periphery of the said blank D.

C' is a broken line indicating the line 110 on which part D' of blank D is bent to form a cylindrical body. Said cylindrical body

is provided with a hole or aperture there-through by means of recess E. Cylindrical body D' is made of suitable diameter to fit closely to the several ears B, after such ears 5 have been formed at right angles to the main body part of blank A and the members obtained from said blanks A and D are joined together. The apertures a' in blank A, and d' in blank D are equally distant from the 10 center of the blanks A and D and are so arranged relative to ears or lugs B and recess E, that when said apertures a'-d' are opposite each other the recess E will come between some two of the lugs B.

15 F, Fig. 9, is a comb provided with fingers f, f', f'', f'''.

G, Figs. 7 and 8, is a pin provided with small ends g, g, which fit into the respective apertures a', d', when the two members of 20 the wheel are assembled.

H is a dog loosely mounted on pin G between the two members obtained from blanks A and D.

h is the engaging end of the pawl or dog 25 H and h' is the opposite end of said pawl. End h' of pawl H comes in contact with the inner face of the cylindrical body D' to limit the outward movement of end h.

I is a spring contained in the wheel and 30 arranged so that the end i thereof engages with the pawl H to yieldingly hold the engaging end h of said dog in an advanced position. When the spring I is made of wire as illustrated in the drawing the pawl 35 H is provided with recess i' in which recess the ends i of said spring are retained to maintain said spring in an operative position.

In assembling the several parts forming the wheel, pawl H is placed on pin G, one 40 of the ends g, g, of said pin G is placed in aperture d' of the member obtained from blank D, the spring I is placed in said member with end i in recess i' and the member obtained from blank A is then joined 45 to said assembled members, with the remaining end g of pin G in aperture a'. Ends g extend through the apertures a', d', so as to be riveted over to hold both members of the wheel firmly in place, and after 50 the several parts are assembled as above set forth said ends are riveted.

J is a shaft forming an element of the device and is provided with a single ratchet tooth j. This ratchet tooth j consists of a 55 properly shaped groove of suitable length cut in shaft J. Any desired number of said wheels are loosely mounted on shaft J.

K is a spring arranged to engage with the periphery of the wheel of the device.

60 The comb F is designed to be suitably mounted and moved reciprocally with the several fingers f, f', f'', f''', thereof in contact with the periphery of one or more of the wheels of the device. The finger f will at each 65 alternate cycle of the movement of the said

comb engage with the edge of one of the lugs B, and move the wheel actuated thereby one step, and when the recess E of said wheel is in position so that said finger f drops thereinto the finger f' will engage with the edge of a lug on the adjacent wheel, of next higher denomination, and said adjacent wheel will also be moved one step. The several recesses E are arranged relative to the numerals on the wheels so that the adjacent wheel of next higher denomination is moved by said comb F when the printing or exposed figure 9 of the wheel of lower denomination is moved and zero substituted in its place.

The operation is the same with all the wheels actuated by a given comb, and the number of said wheels mounted on the shaft J corresponds with the number of fingers on the comb, which may be more or less than is shown in Fig. 9.

When a given count has been obtained from the wheels mounted on shaft J and the wheels are to be re-set at zero, said shaft is turned once around. In turning the shaft J once around, if any of the wheels mounted thereon have not been moved from their initial position said wheel or wheels will be turned once around with said shaft and the zero on said wheel will again be presented to sight or for printing, so that the effect is the same as if said wheel or wheels had not been moved. Those of said wheels which have been moved by comb F will be held stationary by spring K until the pawls H therein are engaged by the turning of ratchet tooth j of shaft K. After the engagement of said ratchet tooth j with pawl H the wheel in which said pawl is mounted will be forced around with the shaft, and when said shaft completes its revolution the zero on said wheel will be exposed to sight or for printing. A single turn of the shaft J therefore re-sets all the wheels mounted thereon which contain a pawl H.

Having thus described my invention what I claim as new and desire to secure by Letters Patent is:—

1. The combination of a member provided with a plurality of lugs arranged in planes concentric to the axis of said member with an additional member provided with a flange fitting said lugs, said members having central openings concentric to said lugs and flange, a pawl mounted between the members, a shaft fitting loosely in said central openings, a ratchet tooth on said shaft, means yieldingly to hold the pawl in position for engagement with said ratchet tooth, and one of said members having numerals on the periphery thereof.

2. A wheel comprising metallic members, one having lugs in planes at right angles to the remaining portion of said member and the other having a cylindrical portion fit-

ing the lugs of the first named member, each of said members having a central aperture, a shaft loosely fitting said apertures, a ratchet tooth for said shaft, a pivotally mounted pawl between the members, means arranged to force the pawl toward said ratchet tooth, and numerals on one of said members.

3. A wheel comprising a plurality of 10 members, one having lugs arranged in planes at right angles to the remaining portion of said member and the other having a cylindrical portion fitting said lugs, each of

15 said members having a central aperture and an additional aperture, a shaft loosely fitting in said central apertures, a ratchet tooth for said shaft, a pin in said additional apertures having provision for holding said members together, a pawl pivoted on said pin between said members, a spring for forcing said pawl toward said ratchet tooth, and numerals on one of said members.

ISAAC S. DEMENT.

In the presence of—

CHARLES TURNER BROWN,
CORA A. ADAMS.
